UNITED STATES PATENT OFFICE

171,369

DRESS

Mamie Verrand, New York, N. Y.

Application July 7, 1953, Serial No. 25,836

Term of patent 3½ years

(Cl. D3—26)

To all whom it may concern:

Be it known that I, Mamie Verrand, a citizen of the United States, residing in New York, in the county of New York, and State of New York, have invented a new, original, and ornamental Design for a Dress, of which the following is a specification, reference being had to the accompanying drawing, forming part thereof.

Fig. 1 is a front view of a dress showing my new design, and

Fig. 2 is the rear view thereof.

I claim:

The ornamental design for a dress, substantially as shown.

MAMIE VERRAND.
